(57) **CLAIM**

The ornamental design for a bottle, as shown and described.

DESCRIPTION

FIG. 1 is a front perspective view of a bottle showing our new design;
FIG. 2 is a side view thereof, of which the opposite side view is a mirror image;

FIG. 3 is a front view thereof, of which the rear view is a mirror image; and,
FIG. 4 is a top view thereof.

The uneven-length and even-length broken lines immediately adjacent to the shaded area define the bounds of the claimed design and form no part thereof. The even-length broken lines depicting the remainder of the bottle form no part of the claimed design.
